SEWING-MACHINE NEEDLE-CONTROLLING MECHANISM

Application filed June 9, 1925. Serial No. 35,854.

This invention relates to improvements in sewing machines more particularly of that class in which means are provided for throwing a needle temporarily out of action during the continued operation of the other mechanism of the machine. The primary object of this invention is to provide a compact, durable and efficient mechanism for automatically recoupling a needle-bar with its actuating mechanism after a predetermined period of operation of the machine subsequently to the throwing out of action under manual control of the disconnected needle-bar, including indicating means successively denoting the cycles of operation of the actuating mechanism of the machine while the needle is disconnected therefrom.

The present needle-bar controlling means comprises an improvement more particularly of the device disclosed in the prior patent of J. Kerr, No. 1,588,030, June 8, 1926. In its preferred embodiment, it is applied to a two-needle sewing machine in which two needle-bars are normally coupled for unison reciprocation and in which one of the needle-bars may be at will disconnected from its actuating mechanism in the production of angular seams. In the formation of seams of this character, the work must be turned by the operator about the operative needle to change the direction of seam-formation, and the present improvement provides means indicating to an operator the exact time when the work must be turned to avoid an elongated or double stitch when the disconnected needle-bar is automatically recoupled with its actuating mechanism, in conformity with the distance between the needles and the length of stitch. The means employed for effecting the automatic re-coupling with its actuating mechanism of the manually disconnected needle-bar comprises in effect an adjustable stitch-counting device, which also indicates the formation of successive stitches by the operative needle while the other needle is idle.

It is essential for efficient operation of the needle-bar controlling device to provide positive means insuring that a predetermined number of stitches will be formed by one needle in the idle period of the disconnected

needle-bar, in correspondence with the operation of the stitch-counting device. To this end the present construction preferably includes a device which permits the needle-bar to be disconnected from its actuating mechanism under manual control during a part only of the stroke of said needle-bar.

In the accompanying drawings, Fig. 1 is a sectional elevation of a portion of the overhanging bracket-arm of a two-needle sewing machine embodying the present improvements, the improved stitch-counting device being disconnected from its actuating mechanism and the needle-bars being shown in full lines as coupled for unison reciprocation. Fig. 2 is a top plan view of the same. Fig. 3 is an enlarged rear side elevation of the stitch-counting device. Fig. 4 is an enlarged perspective view of the counting device, viewed from the rear side of the machine. Fig. 5 is an enlarged transverse sectional view of the counting device. Fig. 6 is a sectional view on the line $x-x$ of Fig. 1. Fig. 7 is a front end elevation of the counting-device bracket. Fig. 8 comprises detail perspective views of the needle-holders. Fig. 9 is a section substantially on the line $y-y$ of Fig. 1. Fig. 10 is a perspective view of the forward end of the counting device bracket.

Referring to the drawings, there is illustrated only so much of the sewing machine as is deemed essential to an understanding of the present invention. The sewing machine includes the usual overhanging bracket-arm 1 terminating at its forward end in the head 2, in which bracket-arm is journaled the rotary main or needle-reciprocating shaft 3. At its forward end, the shaft 3 carries the usual crank-disk 4 connected by means of a link 5 with a stud 6 projecting laterally from a split-collar 7 clamped by means of a screw 8 upon a main needle-bar 9. The needle-bar 9 is journaled for endwise reciprocation in suitable bearings provided by an upper elongated bushing 10 and a lower bushing 11 disposed in aligned apertures in the head 2. The needle-bar 9 is formed with a rectangular groove 12 in which is slidably disposed an auxiliary slab-sided needle-bar 13. The inner surface of the collar 7 is partially cut

away to provide a clearance 14 for the needle-bar 13, whereby the needle-bar 9 may be reciprocated by the link 5 independently of the needle-bar 13. Secured by means of a screw 15 upon the lower end of the needle-bar 9 is a segmental collar 16 of a needle-holder 17 in which a needle 18 is suitably fastened by a set-screw 19. Secured by means of screws, as 20, upon the needle-bar 13 is a collar 21 of an auxiliary needle-holder 22 in which a needle 23 is secured by means of a set-screw 24. As the collar 21 overlies the collar 16, the needle-bar 9 is free to reciprocate independently of the needle-bar 13 when the needle-bars are uncoupled as will hereinafter be described.

Adjacent its upper end, the needle-bar 13 is formed with a laterally extending, apertured lug 25 in which a coupling-pin 26 is slidably disposed to enter an aperture 27 in the needle-bar 9, whereby to compel unison reciprocation of said bars upon rotation of the shaft 3. The lug 25 projects through a slot 28 formed in the bushing 10, and the coupling-pin 26 extends laterally from a vertically apertured coupling-block 29 which is slidably disposed upon a vertical guide-pin 30 carried by a reciprocatory slide-block 31, said slide-block 31 being mounted in a suitable undercut guideway 32 provided in the forward portion 33 of a counting-device supporting bracket 34. The bracket 34 is secured by a screw 35 upon the bracket-arm 1 of the machine and is apertured to embrace the bushing 10 whereby it is fixed against movement. This bracket 34 carries the several elements constituting the stitch-counting device, which is therefore a self-contained unit.

The coupling and uncoupling of the needle-bars is effected by reciprocatory movements of the slide-block 31, the movement to uncouple the bars being manually effected. To this end, the slide-block 31 is connected by means of a link 36 with one end of a lever 37 pivotally supported by a screw 37' in a milled out slot 38' provided in an upstanding lug 38 of the bracket portion 33. The other end of the lever 37 has a ball-joint connection with one end of a link 39 of which the other end is pivotally connected with a vibratory arm 40 fulcrumed upon a stud-screw 41 threaded into the bracket 34. A spring 42 connected at one end with the bracket 34 and at its other end with the arm 40 functions to yieldingly hold said arm in position wherein the needle-bars are coupled for unison reciprocation, this position of the arm 40 being determined by an adjustable stop-screw 43 threaded into a lug 44 upon the bracket 34. The vibratory arm 40 is apertured to receive the offset end of a rod 45 connecting said arm with a two-armed lever 46, fulcrumed upon the machine arm 1 and suitably connected with a treadle (not shown), said lever 46 being acted upon by a spring 47 in the same direction as does the

spring 42 upon the arm 40, i. e., to hold the needle-bars in coupled relationship. The movement of the lever 46 under the action of its spring is preferably limited by a stop-pin 48 which may be adjustably secured in any suitable manner upon the machine-arm. 70

It will be apparent that when the lever 46 is treadle-actuated to swing it in opposition to the spring 47, the arm 40 will be rocked in opposition to the spring 42, which movement is transmitted to the slide-block 31 through the described connections therewith, whereupon the coupling-pin 26 is withdrawn from the needle-bar 9. Means are however provided to prevent the uncoupling of the needle-bars excepting during the upper portion of their stroke, in order to insure that the counting device, to be later described, will register the exact number of reciprocations of the needle-bar 9 while the needle-bar 13 is idle. To this end a bracket 49 is secured by screws, as 50, upon the front face of the lug 38, which bracket is provided at its lower end with a laterally extending stop-member 51. The stop-member 51 is so disposed with respect to the coupling-block 29 as to permit vertical reciprocations of said block but so as to prevent a lateral uncoupling movement thereof during the lower portion of the stroke of the needle-bar 13. 95

The disconnected needle-bar 13 is carried to the upper end of its stroke by the needle-bar 9 and it is retained in this position until again automatically re-coupled with the bar 9. The retaining means comprises a shoulder 52 of a pawl 53 which is pivotally mounted upon the bracket 49 by a pivot-screw 54 and is normally spring-pressed against the bracket member 51 by a spring 55. The shoulder 52 snaps under the coupling-block 29 when the latter is shifted laterally for disconnecting the needle-bar 13 and as said needle-bar reaches the upper end of its stroke. The upstroke of the disconnected needle-bar is preferably limited by a buffer-rod 56 disposed to overlie the needle-bar, said rod 56 being slidably mounted in the bracket-lug 38 and acted upon by a spring 57 to yieldingly hold it in a position determined by a collar 58 upon the rod and resting upon the upper side of the lug 38. 110

Improved mechanism, constituting in effect a stitch-counting device, is provided for automatically re-coupling the disconnected needle-bar with the continuously reciprocated needle-bar after a predetermined number of reciprocations of the latter subsequently to the throwing out of operation of the needle-bar 13. To this end, the vibratory arm 40 carries a pin 59 which in the connected position of the needle-bars overlies the forward end 60 of a latch-lever 61 pivotally mounted upon the rear face of the bracket 34 by means of a pivot-screw 62. The under side of this latch-lever 61 is engaged by a 115

plunger 63 slidingly mounted in a socket 64 of the bracket 34 in which socket is disposed a spring 65 which urges said latch-lever upwardly. The latch-lever 61 is formed at its forward end with a latching-notch 66 and on its upper side with a flat surface 67. When the vibratory arm 40 is actuated to disconnect the needle-bars and the latch-pin 59 rides off the forward end 60 of the latch-lever into alinement with the notch 66 whereupon said lever 61 snaps upwardly into latching position under the action of the spring 65. Consequently after manual actuation of the arm 40 to disconnect the needle-bar 13, said arm 40 is locked in this position. To release the arm 40 from the latch-lever 61 after a predetermined period of operation of the machine there is provided a tappet 68 of which the hub is secured by means of a spot-screw 69 upon one end of a shaft 70. The shaft 70 is journaled for rotary movements within the bore of a sleeve 71 which is itself journaled for rotation within a stationary bushing 72 fixed by means of a set-screw 73 within a suitable aperture formed in the bracket 34. Mounted upon one end of the sleeve 71 adjacent a flange 74 thereof is an indicator-disk 75 which is fixed to said sleeve by a plurality of pins, as 76, and is disposed in contact with the front face of the bracket 34 to prevent endwise movement of the sleeve 71 in one direction.

The shaft 70 extends outwardly beyond the disk 75 and slidingly secured thereupon, by means of a spline 77, is a tappet-adjusting member 78 having a manipulating knob 79. Formed upon the end of the shaft 70 opposite to the tappet 68 is a shaft-head 80 disposed within a recess 81 formed in the knob 79 and interposed between said head 80 and the base of the recess 81 is a coil-spring 82 which functions to yieldingly hold the adjusting member 78 in contact with the disk 75. Carried by the adjusting-member 78 is a locking-pin 83 adapted to enter any one of a plurality of radially equidistant apertures 84 formed in the disk 75, which is suitably graduated to number said apertures on the side of said disk facing the machine operator. It will be apparent from the foregoing description that by pulling upon the knob 79, the adjusting member 78 may be moved longitudinally of the shaft 70 against the action of the spring 82 to withdraw the locking pin 83 and reposition it in the desired aperture 84. By this repositioning movement, the position of the tappet 68 is adjusted with respect to the latch-lever 61 because of the spline 77 connection between the member 78 and the shaft 70.

The movement of the arm 40 to disconnect the needle-bar 13 from the needle-bar 9 throws into effective action an operating mechanism which intermittently advances the tappet 68 into engagement with the latch-

lever 61 to release the latter from the pin 59 at a predetermined cycle of operation of the machine, whereupon the spring 42 acts upon the arm 40 to re-couple the needle-bars in the upper position of the needle-bar 9. To this end, a rocker-arm 85 is journaled for oscillatory movement upon an enlarged portion 86 of the bushing 72 formed with an arcuate recess 87. The rocker-arm 85 has a ball-joint connection with one end of a pitman 88, 75 which passes through a suitable aperture formed in a cover-plate 89 of the machine bracket-arm 1. The other end of the pitman is formed with a strap 90 which embraces an eccentric 91 upon the shaft 3, and consequently the arm 85 is continuously rocked during the operation of the machine. Pivotally mounted upon the rocker-arm 85, by means of a pivot-bolt 92 is a pawl 93 having an actuating tooth 94 adapted in the operative position of the pawl to engage the teeth 95 formed on a portion of the periphery of a ratchet-wheel 96. The hub of the ratchet-wheel is secured by a spot-screw 97 upon the sleeve 71. 90

Disposed within the bushing recess 87 is a coil-spring 98 of which one end 99 enters a suitable aperture in the ratchet-wheel 96 and the other end 100 enters an aperture in the bushing-shoulder 86. By adjusting the bushing circularly within its support, the tension of the spring 98 may be varied. The periphery of the ratchet-wheel 96 opposite to the teeth 95 is partially cut away to provide a stop-shoulder 102 which is yieldingly held, by the action of the spring 98, in engagement with a stop-screw 103 adjustably secured in a suitable manner in an apertured ear 104 provided on the bracket 34. A bent flat spring 105, which is secured by a screw 106 upon the rocker-arm 85, acts upon the pawl 93 to yieldingly urge said pawl to operatively engage the ratchet-teeth 95. 100

Pivotedly mounted upon the frame 34 by means of a pivot-screw 107 is a stop-pawl 108 which is urged by a spring 109 to engage the ratchet-teeth 95 to prevent retrograde movement of said ratchet-wheel during the return movements of the actuating pawl 93 when the latter is in its effective position. In the coupled relationship of the needle-bars, however, both the actuating pawl 93 and the stop-pawl 108 are held out of engagement with the ratchet-teeth 95 by the provision upon said stop-pawl 108 of a shoulder 110 which is engaged by a pin 111 carried by the arm 40 and by disposing the end of the stop-pawl 108 below the free end of the actuating pawl 93. Consequently while the arm 40 is held against the stop-screw 43, the pin 111 holds the stop-pawl and the latter holds the actuating pawl out of engagement with the ratchet-teeth 95. 115 120 125

In the normal operation of the machine, as before indicated, the needle-bars 9 and 13 are 130

coupled for unison reciprocation and the arm 40 is held against the stop-screw 43 by the spring 42, whereby the latch-pin 59 holds the latch-lever 61 depressed and the pawl-shifting pin 111 holds the pawls out of engagement with the ratchet-teeth 95 so that the arm 85 rocks idly. When approaching an angle in the seam, it is necessary to throw one of the needles out of operation and hold it out of operation until the other needle has made a definite number of stitches up to and beyond the seam angle, consistent with the distance between the needles and the length of stitches made. If this is not done, the seam will manifestly not comprise spaced parallel lines of uniform stitches throughout.

Consequently when it is desired to make an angle seam, the operator adjusts the position of the tappet 68 in accordance with the number of corner stitches to be made by the needle-bar 9, this adjustment being effected by manipulating the adjusting member 78 to position the locking pin 83 in the desired aperture 84. For instance, if it is desired to make eight corner stitches, the pin 83 is inserted in the aperture numbered as 8. As the stitching approaches the angle-vertex, the operator actuates a treadle to rock the lever 46, whereby the arm 40 is swung in a direction to permit the latch-pin 59 to ride off the end of the latch-lever 61 into the latching notch 66 thereof and to uncouple the needle-bar 13 from the bar 9 through the described connections, although the uncoupling movement will be permitted only during the upper portion of the stroke of the needle-bars because of the stop-member 51. The needle-bar 13, while idle, is retained at the upper end of its stroke by the holding pawl 53 and the buffer-rod 56. The movement of the arm 40 to uncouple the needle-bars causes it to carry the pawl-shifting pin 111 into a position permitting both pawls 93 and 108 to engage the ratchet-teeth 95 whereupon the continuous rocking movements of the arm 85 are rendered effective to cause intermittent rotative movements of the ratchet-wheel 96 and thereby cause the tappet 68 to approach the latch-lever 61 step-by-step, i. e., one advancing movement for each stitch made by the needle-bar 9.

As the indicator-disk 75 is rigidly secured to the ratchet-wheel 96, it is also rotated step-by-step, i. e., stitch-by-stitch, the number of stitches of advance of said disk 75 being indicated to the machine operator by a pointer 112 secured by means of a screw 113 upon the bracket 34. When half of the total number of corner stitches have been made, which fact is indicated to the operator by the disk 75 and pointer 112, the operator turns the work to form the desired angle of seam and when the total number of corner stitches have been made, the tappet 68 acts upon the surface 67 of the latch-lever 61 to release said

latch-lever whereupon the parts are automatically returned to initial position to recouple the needle-bars, the disk 75 being also returned to initial position determined by the engagement of the stop-shoulder 102 with the stop-screw 103 effected by the spring 98.

Having thus set forth the nature of the invention, what I claim herein is—

1. In a sewing machine, the combination with two needle bars, actuating mechanism for reciprocating said needle-bars, and controlling means for uncoupling one of said needle-bars from its actuating mechanism during the operation of the machine, of a latch-lever for holding said controlling means in needle-bar uncoupled position, a latch-lever releasing tappet, a tappet adjusting member, an indicator-disk, means including a spring for yieldingly locking said adjusting member to said indicator-disk, and operating mechanism brought into effective action by the operation of said controlling means for intermittently rotating said indicator-disk and tappet to release said latch-lever.

2. In a sewing machine, the combination with two needle-bars, actuating mechanism for reciprocating said needle-bars, and controlling means for uncoupling one of said needle-bars from its actuating mechanism during the operation of the machine, of means for latching said controlling means in needle-bar uncoupled position, and a counting device for releasing the controlling means from its latching means after a predetermined interval of operation of the continuously reciprocated bar, said counting device comprising a stationary supporting frame, a continuously actuated rocker-arm fulcrumed upon said frame, an actuating pawl carried by said arm, a ratchet-wheel journaled upon said frame, an indicator disk secured to said ratchet-wheel, a rock-shaft, an adjusting member splined upon said rock-shaft, means including a spring for adjustably locking said adjusting member to said indicator disk, and a tappet carried by said rock-shaft for releasing said latching means.

3. In a sewing machine, the combination with two needle-bars, actuating mechanism for reciprocating said needle-bars, and manually controlled means for uncoupling one of said needle-bars from its actuating mechanism during the operation of the machine, of a stop-member limiting the effective operation of said manually controlled means to the upper portion of the stroke of said needle-bars, and mechanisms for automatically recoupling said needle-bars.

4. In a sewing machine, stitch-forming mechanism including a reciprocatory needle, actuating mechanism for reciprocating said needle, a normally inactive indicating device, and means manually operable during a portion only of a cycle of operation of the machine for initiating the operation of said in-

dicating device in timed relation with respect to said needle-actuating mechanism to definitely denote to an operator the number of the instant cycle of operation of the machine in a plurality of successive cycles of operation thereof.

5. In a sewing machine, stitch-forming mechanism including a reciprocatory needle, actuating mechanism for reciprocating said needle, a normally ineffective stitch-counting device, and means manually operable during a portion only of a cycle of operation of the machine for rendering said needle inoperative and initiating the operation of said 10 counting device in definitely timed relationship with respect to said actuating mechanism.

6. In a sewing machine, stitch-forming mechanism including a reciprocatory needle, actuating mechanism for reciprocating said needle, a stitch-counting device, means manually operable during a portion only of a cycle of operation of the machine for rendering said needle inoperative and initiating the 15 effective operation of said counting device, and means controlled by said counting device for automatically rendering operative the inoperative needle.

7. In a sewing machine, stitching-forming mechanism including a reciprocatory needle, actuating mechanism for reciprocating said needle, a normally ineffective stitch-counting device, means manually operable during a portion only of a cycle of operation of the 20 machine for initiating the effective operation of said counting device in definitely timed relationship with respect to said needle-actuating mechanism, and means for automatically returning the counting device to initial position after a predetermined number of cycles 25 of operation of the machine have been counted thereby.

8. In a sewing machine, stitch-forming mechanism including a plurality of reciprocatory needles, actuating mechanism for reciprocating said needles, means manually operative during a portion only of any complete cycle of operation of the machine for disconnecting one of said needles from its actuating mechanism, a stitch-counting device 40 brought into effective operation as said needle is rendered inoperative in definitely timed relationship with respect to said actuating mechanism, and automatically acting means for re-connecting said needle with its actuating mechanism and rendering said counting device inoperative.

9. In a sewing machine, stitch-forming mechanism including a reciprocatory needle, actuating mechanism for reciprocating said needle, means manually operable during a portion only of a complete cycle of operation of the machine for disconnecting said needle from its actuating mechanism, a 45 counting device brought into effective oper-

ation by said needle-disconnecting means for automatically controlling the re-coupling of the needle with its actuating mechanism, and adjustable means for predetermining the re-coupling action of said counting device.

10. In a sewing machine, in combination, a needle-carrying bar, actuating mechanism for endwise reciprocating said bar, manually controlled means operable during a portion only of any complete cycle of operation of the machine for disconnecting said bar from its reciprocating means, a counting device thrown into effective action in definitely timed relationship with respect to said actuating mechanism by the operation of said manually controlled means for predetermining the period of inactivity of the disconnected bar, and an indicator associated with said counting device for visibly denoting to an operator the number of the instant cycle 70 of operation of said actuating mechanism in the successive cycles of operation during the period of inactivity of the disconnected needle-bar.

11. In a sewing machine, in combination, a needle-carrying bar, actuating mechanism for endwise reciprocating said bar, manually controlled means for disconnecting said bar from its reciprocating means during the operation of the machine, a normally ineffective counting device mounted in fixed position upon the machine frame, means for bringing said counting device into effective operation by the operation of said manually controlled means, and a spring controlled by 90 said counting device for effecting re-coupling 95 of said needle-bar with its actuating mechanism.

In testimony whereof, I have signed my name to this specification.

FREDERIC M. CARD.
